SAMUEL A. WICKMAN, OF ST. ALBANS, NEW YORK, ASSIGNOR TO AMERICAN MACHINE & FOUNDRY COMPANY, A CORPORATION OF NEW YORK

PUSHER DEVICE FOR EXTRA LONG LOAVES

Application filed August 21, 1931. Serial No. 558,630

This invention relates to package conveyors for wrapping machines, particularly to conveyors of the chain and pusher type for acting on bread loaves and packages of greatly varying length. The principal object of the invention is to provide extra pusher fingers for long packages while avoiding certain difficulties and interference of parts which would normally result in such a construction.

Certain modern wrapping machines are intended to act on loaves or packages varying greatly in length as for instance from 7" to 22". It has been found that with the long loaves or packages, particularly with long sliced bread loaves that the articles if engaged near the center by pusher fingers properly spaced for normal or short articles, tend either to curve about the pushers at the center or to swing about the pushers as a pivot. Accordingly it is an object of the invention to provide a practical construction by which the proper number and arrangement of pushers for long loaves or articles may be provided at will. This however involves the difficulty that the end pusher fingers would interfere with the end closing or folding and sealing mechanism when said mechanisms were at their inner positions for acting on the short articles. Accordingly another object of the invention is to provide for releasably securing end pushers in a simple and practical manner either in or out of operative position so that they may at will be conveniently secured in position to clear the folding or closing plates with the ultimate object of producing a wrapping machine which works satisfactorily with articles varying very widely in dimension. With these and other objects not specifically mentioned in view, the invention consists in certain constructions and combinations which will be hereinafter fully described and then specifically set forth in the claims hereunto appended.

In the accompanying drawing, which forms a part of this specification and in which like characters of reference indicate the same or like parts, Fig. 1 is a side elevation of the long loaf pusher arrangement used in conjunction with a bread wrapping machine; Fig. 2 is

an end elevation of the mechanism shown in Fig. 1; Fig. 3 is a detail sectional view of the locking device of the folding fingers and Fig. 4 is an end elevation of Fig. 3.

In carrying the invention into effect there is provided in combination with a primary set of pusher fingers for pushing articles through a wrapping machine, a secondary series of fingers on either side of and having the same movement as the primary series when an extra long article is to be wrapped, and means whereby said secondary series are incapacitated when articles of normal length are wrapped. In the best constructions the fingers of the secondary series are swingable in and out of position to act on the article and preferably means are provided for releasably holding them in either position.

Referring to Figs. 1 and 2, the endless conveyor chains 10 run over rear sprockets 11, fixedly attached to drive shaft 12, and over a pair of front sprockets not shown. Cross members 13 mounted in bearings 14 attached at equal distances to the endless chains 10 carry two pairs of pusher fingers 15, 15 and 16, 16, the fingers of the former pair being fixedly attached to the member 13 by means of clamp lugs 17 while those of the latter pair are removably mounted on the member 13. The long loaf L which rests on table 18 is conveyed by the pusher fingers 15 and 16 past wrapping or sealing devices such as the folder plates 19 and 20 for closing the end flaps of a partially wrapped article carried by brackets 21 and 22 adjustably mounted on a screw rod 23 the brackets and screw rod being suitably guided in the machine frame, not shown. Arms 24, attached to the cross members 13 of the conveyor, support rollers 25 which serve to guide the pusher fingers 15 and 16 by engaging with a guide rail 26 on their travel around with the conveyor.

The releasably mounted pusher fingers 16 are held in position on the members 13 by radial plugs 27, Figs. 3 and 4, carried in their hubs, engaging in each of which is a spring pressed plunger 28 held in a hole 29 provided for this purpose in cross member 13, by a spring 30, said plunger being fastened

to a knurled knob 31. By lifting the plungers 28 out of the holes 29, the fingers 16 may be incapacitated by sliding them to the ends of the respective members near each of which 5 each member has an annular groove 32, Fig. 2, into which fits the locking plunger 28 of the finger. In positions corresponding with the grooves 32 on cross members 13, the cross rods 33, which are mounted in bearings 34 10 attached to the chains 10 on which the pusher fingers of each cross member rest on their return travel, carry swingable members 35 held in annular grooves 36 by set screws 37. Each member 35 has a horizontally projecting 15 pin 38 and the rearwardly projecting web of each of the extra fingers 16 has a hole 39, so that the fingers 16 can be locked to the flanges 35 when not in use, the fingers then remaining in their inoperative position on 20 rods 33 on the forward travel of the member 13 as well as on their return travel. In this position they clear without interference the wrapping devices 19 and 20. The swing of members 35 provides relative longitudinal 25 movement of the free end of the fingers with respect to the chain to permit travel around the end loops of the chain.

When the machine is used for wrapping long loaves L, the folder plates 19 and 20 are 30 set wide apart as shown and all the fingers 15 and 16 engage with the loaf. When small loaves L' are to be wrapped, the adjusting rod 23 is turned by a knob, not shown, until the distance of the folder plates 19 and 20 35 corresponds to the smaller length of loaf L' and then only the inner fingers 15 are in position to engage with the loaf. For small loaves it is therefore necessary to lift the outer fingers 16 out of the way and suspend 40 them so that they will not interfere with the brackets 21 and 22. To do this, the operator pulls the knob 31 outward, thereby removing the plunger 28 from the locking hole 29, then turns the finger back until 45 it rests on cross rod 33 and slides it axially outward on member 13 with one hand while with the other he turns the flange 35 on rod 33 so that the pin 38 will enter the hole 39 when the plunger 28 approaches the flange, 50 after which he keeps on sliding the finger until the plunger 28 engages with the corresponding groove 32 of cross members 13 and snaps into the same, thereby locking the finger to the rod 33. The fingers 16 are carried around on the chains 10 in this suspended 55 position until they are again placed in working position when required.

Thus a proper distribution of the pushing forces from the several pushing fingers is attained, whereby there will be no tendency of articles to bend between or beyond pushers and whereby no interference with use of the wrapping machine on articles of all lengths within its capacity results.

65 What is claimed is:

1. The combination with a primary series of traveling fingers for pushing articles through a wrapping machine, of a secondary series of fingers on either side of and having the same movement as the primary series 70 when extra long articles are to be wrapped, and means whereby said secondary series are incapacitated when articles of normal length are to be wrapped.

2. The combination with a primary series 75 of traveling fingers for pushing articles through a wrapping machine, of a secondary series of fingers on either side of and having the same movement as the primary series when extra long articles are to be wrapped, 80 and means whereby said secondary series are incapacitated when articles of normal length are to be wrapped, the fingers of said secondary series being swingable in and out of position to act on the articles. 85

3. The combination with a primary series of traveling fingers for pushing articles through a wrapping machine of a secondary series of fingers on either side of and having 90 the same movement as the primary series when extra long articles are to be wrapped, means whereby said secondary series are incapacitated when articles of normal length are to be wrapped, the fingers of said secondary series being swingable in and out 95 of position to act on the articles, and means for selectively holding them in either position.

4. The combination with an endless chain 100 conveyor having a primary series of fingers for pushing articles through a wrapping machine, and a secondary series of fingers having the same movement as the primary series when extra long articles are to be wrapped, means whereby said secondary series are incapacitated when articles of normal length are to be wrapped, the fingers of 105 said secondary series being swingable in and out of position to act on the articles, means for selectively holding them in either position, 110 said means including elements on a chain of said conveyor and coacting with the secondary pushers to yieldingly support the same thereon while permitting the pushers 115 to follow around a loop of the chain.

5. The combination with separated wrapping devices for closing package wrappers, means mounting said devices for movement toward or away from each other to act on 120 different lengths of packages, a primary series of traveling fingers for pushing articles between the devices, a secondary series of fingers on either side of and having the same movement as the primary series when extra 125 long articles are to be wrapped, said closing devices being adjustable to positions in path of the secondary fingers when the devices are in position for operating on extra length packages, and means for incapacitating said 130

secondary series of fingers and holding them in inoperative position clear of said devices when short length articles are wrapped.

6. The combination with separated wrapping devices for closing package wrappers, means mounting said devices for movement toward or away from each other to act on different lengths of packages, a primary series of traveling fingers for pushing articles between the devices, a secondary series of fingers on either side of and having the same movement as the primary series when extra long articles are to be wrapped, said closing devices being adjustable to positions 10 in path of the secondary fingers when the devices are in position for operating on short length packages, means for incapacitating said secondary series of fingers and holding them in inoperative position clear of said 15 devices when short length articles are wrapped, spaced parallel chains, cross members on said chains on which secondary fingers are swingably mounted, said means including a spring pressed plunger and recess construction for releasably securing the finger 20 against swinging on the shaft.
- 25

In testimony whereof, I have signed my name to this specification.

SAMUEL A. WICKMAN.
